UNITED STATES PATENT OFFICE.

FRANK S. ALIANO, OF NEW YORK, N. Y.

LOCK.

SPECIFICATION forming part of Letters Patent No. 760,599, dated May 24, 1904.

Application filed September 4, 1903. Serial No. 171,918. (No model.)

To all whom it may concern:

Be it known that I, FRANK S. ALIANO, a citizen of the United States, residing in the borough of Brooklyn, city of New York, county of 5 Kings, and State of New York, have invented certain new and useful Improvements in Locks, of which the following is a specification, reference being had therein to the accompanying drawings, which form a part thereof.

10 My invention relates to improvements in locks, and more particularly to a class of spring-locks wherein the bolt or bolts are adapted to automatically enter its or their sockets when the lock is closed.

15 The object of my invention is to provide a lock of this character which will be composed of elements readily manufactured at small cost and so assembled as to produce a simple mechanism in compact form.

20 A further object is to provide a lock wherein the bolt or bolts may to lock the device act solely under their own spring tension or may be shot positively through the medium of a key.

25 A still further object is to provide a lock which is especially adapted to be attached to and form a part of the hasp of a trunk or similar lock; and a still further object is to provide a lock of this character wherein the several parts will be so related as to give great 30 stability to the assembled structure.

The invention consists in the novel features of construction hereinafter set forth and described, and more particularly pointed out in 35 the claims hereto appended.

Referring to the drawings, Figure 1 is a side elevation of a trunk-lock embodying the preferred form of my invention, the lock proper being in section on the line 1 1 of Fig. 2. 40 Fig. 2 is a plan view thereof on the line 2 2 of Fig. 1 with the hasp broken away to disclose the actuating mechanism contained in the tumbler-chamber of the lock-casing. Fig. 3 is a horizontal section on the line 3 3 of Fig. 45 1. Fig. 4 is a perspective view of the under side of the key-disk. Fig. 5 is a view of a modified form of my invention, the bolt-chamber and bolt being in section; and Fig. 6 is a horizontal section on the line 6 6 of Fig. 5.

Like letters refer to like parts throughout the several views.

In the drawings, A and B indicate the parts which respectively carry the lock-hasp C and the socket-plate D. The construction and arrangement of these parts, except the detailed 55 construction of the socket-plate D, are well-known in this art and form no part of this invention. The hasp C carries the lock-casing, which is constituted of two superposed cylindrical portions *a* and *b*, forming an upper or 60 tumbler chamber *a'* and a lower or bolt chamber *b'*. The tumbler-chamber *a'* is of greater diameter than the bolt-chamber *b'*, which arrangement results in the formation of the offset portion *c* presenting upwardly within the 65 chamber *a'* a seat and bearing for the tumblers and a support for the tumbler pivot-pin and for the tumbler-springs-tensioning pin and downwardly a contact-face adapted to engage the socket-plate D. The said casing is closed 70 by the bottom plate *d*, and preferably all parts thereof are made integral, being either stamped or turned from a single piece of metal.

The bottom plate *d* has firmly attached 75 thereto the key-stud *e*, which extends to a point adjacent to the top of the tumbler-chamber *a'*.

Substantially oppositely disposed bolt-holes are provided in the portion *b*, and seated 80 in the bolt-chamber *b'* and projecting through these openings are bolts *f* and *g*. The bolts are disposed upon opposite sides of the stud *e*, rest upon the bottom plate *d*, and move in a way formed by said stud and the spring-seats *h* and *i*. The detailed construction of 85 said bolts and their spring-seats being identical, a detailed description of but one of them will be entered into, the corresponding part in the other bolt being designated by the second reference-letter in each instance.

Each bolt consists of the locking portion having the usual plane face adapted to engage the lock-socket and the beveled surface adapted to engage said socket to retract the bolt 95 to insure an automatic engagement of the bolt therewith. This portion of said bolt differs from the ordinary bolts solely in that the

outer edge thereof is curved, as at $f' g'$, to conform with the contour of the portion b , and thus insure a complete retraction of the bolt within the chamber b' or its bolt-hole 5 without sacrificing the gripping area of the bolt. Within the bolt-chamber b' the side of the bolt toward the stud e is reduced to provide a narrow shank $f^2 g^2$ with the twofold object to permit the bolt to slide freely past 10 said stud and to provide suitable space for the means actuating said bolts. The shank $f^2 g^2$ on its outer side is provided with an abutment $f^3 g^3$, the opposite sides of which, respectively, are curved so as to serve by 15 engagement with the portion b to limit the extent of projection of the bolt therefrom and flat to act as a seat for the spring $j j'$. A shoulder $f^4 g^4$ on said shank is so disposed thereon as to engage the spring-seat $h i$ to 20 limit the extent of retraction of the bolt by the key. The said bolt-shank $f^2 g^2$ has on its lower face adjacent to said stud e a channel cut away, as shown in Fig. 1 at $f^5 g^5$, the object of which cut will appear hereinafter. 25 The upper face of said shank is provided with a way disposed between said stud e and the portion b , as at $f^6 g^6$, and the outer corner of said way is scarfed away slightly to facilitate the engagement and disengagement of the 30 actuating mechanism with said bolt.

The spring-seats $h i$ each preferably consist of an L-shaped piece of metal soldered to the portion b , and the springs $j j'$ are respectively disposed between the short arm of said 35 seats and the seats formed by the abutments $f^3 g^3$, the long arm of said seats serving to confine the springs $j j'$ to the chamber formed thereby, together with the bottom d and the closure of the chamber b' .

40 A link k is pivotally mounted on the stud e and projects laterally thereof into engagement with the cuts $f^5 g^5$, the function of said link being to insure synchronous movement of said bolts under all conditions of service 45 and wear. The sides of this link are preferably curved to prevent any tendency to bind in said channel and to avoid the sacrifice of strength of material in the bolts.

The actuating mechanism comprises a rotary key-disk m , pivotally mounted on the stud e , which is fitted to and closes the mouth of the chamber b' , being flush with the annular offset portion c and therewith constituting the bottom of the chamber a' . This disk m 55 rests directly upon the bolts f and g and confines these bolts within the chamber b' , holding them firmly in place in a manner to insure against their displacement through any strains and pressures placed thereupon. To increase 60 the efficiency of the said disk for this purpose, I extend the tumbler-catch m' carried thereby to a height which will insure its engaging the hasp or other plate closing the chamber a' , and also provide a second bearing-piece m^2 of 65 similar height, so disposed on said disk as not

to interfere with the free rotation thereof by contact with other parts of the actuating mechanism.

The disk m is provided with two downwardly-projected rounded studs $m^3 m^3$, arranged eccentrically of said disk, which normally are seated in the space in the chamber b' between the shanks $f^2 g^2$ opposite to the ways $f^6 g^6$, which they are adapted to enter when the disk is rotated. 75

A tumbler fulcrum-pin n is permanently attached to or mounted on the abutment c , said pin being of sufficient height to engage the hasp or other closure plate to give rigidity thereto. Mounted upon this pin are a plurality of tumblers n' of well-known construction, adapted to coöperate with the tumbler-catch m' to prevent the rotation of the disk m . These tumblers are of sufficient thickness to extend to the top of the chamber a' , thus avoiding their disarrangement. A second pin o is also mounted on the said shoulder or abutment c in such juxtaposition to the pin n as to serve as a retaining and tensioning means for the tumbler-springs o' . The lowermost tumbler n' and spring o' rest upon the abutment or shoulder c . 85 90

The disk m is provided with the usual key-recess m^4 in the usual relation to the tumblers.

A further detailed description of the tumblers and their mode of operation will not be entered into, such being old and well known in this art. 95

In the modification shown in Figs. 5 and 6 the construction is identical with that of the preferred form, except that a single bolt q is employed. This bolt is provided with the curved outer edge q' and with a central slot forming the double shank $q^2 q^2$, each having an abutment $q^3 q^3$, which limits the extent of projection of the bolt and acts as a double spring-seat. The spring-seats r , however, are formed of a single metal blank, the rear of which forms a way for the bolt and also serves to limit the amount of retraction of the bolt. 100 The bolt is provided with but a single way s , which is adapted to coöperate with a single stud m^7 , carried by the rotary key or actuating disk m . Normally the said stud m^7 is seated in the slot in the bolt, so that, as in the preferred form of the invention, the said bolt may be sprung and shot without any movement of the actuating mechanism. 110 115 120

In both forms of the invention the ways $f^6 g^6$ and s are of a width but slightly greater than that of the studs $m^3 m^3 m^7$, so that said studs will engage both sides of the said ways, and thus permit the use of the key in both retracting and shooting the bolts. 125

The socket-plate D comprises the ordinary face-plate u , having an annular flange u' of such thickness as to as nearly as possible occupy the space between the downwardly-exposed face of the abutment c and the plane face of the bolt or bolts and of a width to 130

leave a circular opening of approximately the width of the portion b , thus serving as a seat for the said abutment and to engage the bolts both in a manner to insure a close relation 5 of these parts when the lock is closed.

The operation of the foregoing mechanism, in so far as has not already been described, is as follows: Assuming the lock to be open, to close it it is merely necessary to press it 10 against the socket-plate, which action brings the bolts f, g into engagement with the flange u' , which engagement by reason of the beveled face of said bolts forces them within the bolt-chamber b' against the tension of the springs 15 j, j' , respectively, to a point where the said bolts pass said flange, whereupon under the said spring tension they are automatically shot or projected from the said chamber beneath said flange. The curved shoulder of each 20 abutment f^3, g^3 , in conjunction with the opposed spring action, serves to hold the bolts steady longitudinally, said bolts laterally and vertically being steadied by the way formed by the stud e and spring-seats h and i and by 25 the disk m and the bottom plate d , respectively. It will be observed that the bolts are the only parts of the lock mechanism affected by this operation, excepting the link k , which insures synchronous action of both bolts. The 30 curved edge of each bolt insures the complete retraction thereof within the bolt-chamber and also a proper clearance of the socket-plate flange with a minimum movement of the bolts. The abutment c rests upon the said plate, and 35 as the space between said abutment and said bolt is approximately equal to the thickness of the flange there is no looseness of the lock when closed. To release the lock, it is merely necessary to rotate the disk m upon the stud 40 e by means of a special key adapted to actuate the tumblers n' in the usual manner to release the catch m' and to permit such rotation. The tumblers and their springs being mounted 45 on an immovable portion of the casing are not affected by the movement of parts, and their fulcrum-pin and tension-pin are so disposed as to require no special construction of any of the working parts. The said disk m is held 50 in place by the catch m' and the bearing-piece m^2 , both of which engage the upper closing-plate of the lock, as the hasp C . As the plate or disk m is turned the studs m^3, m^3 , which heretofore were seated in the space between the bolt-shanks and inoperative, each enter one of the 55 ways f^6, g^6 in the bolts f, g , respectively, and engages the rear bearing-face thereof, and as the disk is further rotated the bolts are forced inwardly thereby against the tension of the bolt-springs. It will be observed that, except 60 when the wear-surfaces are not accurately adjusted, the link k is substantially inoperative during this action. If there is a tendency on the part of the bolts to bind in any way, positive pressure may be brought to bear on said 65 bolts by the rotation of the disk m in the re-

verse direction, the studs m^3, m^3 being adapted to engage the opposite face of the way f^6, g^6 during such reverse movement. The springs j, j' , however, are usually of sufficient tension to shoot the bolts, and by reason of the scarfed 70 corners of said ways and the rounded surface of the studs m^3, m^3 the disk m and its tumblers will normally be automatically restored to their original inoperative position.

The operation of the modification shown in 75 Figs. 5 and 6 is substantially identical with that of the preferred form, except that the single bolt q is actuated instead of two bolts simultaneously.

It will be observed that by the construction 80 heretofore shown and described a reliable spring-lock is obtained the parts of which are simple in their construction and so assembled as not to be liable to disarrangement or undue wear and that the arrangement of bolts 85 is such as to insure a proper resistance throughout to the various strains thereupon when they are shot.

The minor details of construction may be 90 varied to adapt the lock to different uses without departing from the spirit and scope of my invention.

Having described the invention, what I 95 claim as new, and desire to have protected by Letters Patent, is—

1. In a lock, the combination of a casing composed of superposed cylindrical portions of different diameters connected by an offset portion, forming respectively a bolt and a tumbler-chamber, a bottom for said casing, a 100 sliding bolt seated thereon and projecting through the side of said casing, a spring acting on said bolt, means whereby said bolt may be retracted against the tension of said spring, and a socket-plate. 105

2. In a lock, the combination of a casing composed of superposed cylindrical portions of different diameters connected by an offset portion, forming respectively a bolt and a tumbler-chamber, a bottom for said casing, a 110 sliding bolt seated thereon and projecting through the side of said casing, a spring acting on said bolt, a rotary disk seated on said bolt, means carried by said disk normally disengaged therefrom but adapted to engage and reciprocate said bolt, a plurality of tumblers mounted on said offset portion, a catch carried by said disk adapted to coöperate with 115 said tumblers, and a socket-plate.

3. In a lock the combination of a casing 120 composed of superposed cylindrical portions of different diameters connected by an offset portion, forming respectively a bolt and a tumbler-chamber, a bottom for said casing, a key-stud secured to said bottom and projected 125 adjacent to the top of said tumbler-chamber, a sliding bolt seated on said bottom and projected through the side of said casing, a spring acting on said bolt, a rotary disk pivotally mounted on said stud and seated on said bolt, 130

means carried by said disk normally disengaged from but adapted to engage and reciprocate said bolt, a plurality of tumblers mounted on said offset portion, a catch carried by said disk adapted to coöperate with said tumblers, and a socket-plate.

4. In a lock, the combination of a casing composed of superposed cylindrical portions of different diameters connected by an offset portion, forming respectively a bolt and a tumbler-chamber, a bottom for said casing, a key-stud secured to said bottom and projected adjacent to the top of said tumbler-chamber, a plurality of sliding bolts disposed on opposite sides of said stud in said chamber and seated on said bottom, projecting through the sides of said casing in opposite directions, spring-seats in said chamber forming, with said stud, ways for said bolts, springs seated in said spring-seats acting on said bolts respectively, a rotary disk pivotally mounted on said stud and seated on said bolts, means carried by said disk normally disengaged from but adapted to engage and reciprocate both
- 15 20 25
- said bolts, a plurality of tumblers mounted on said offset portion, a catch carried by said disk adapted to coöperate with said tumblers, and a socket-plate.

5. In a lock, the combination of a casing composed of superposed cylindrical portions of different diameters connected by an offset portion forming respectively a bolt and a tumbler-chamber, a bottom for said casing, a sliding bolt seated thereon and projecting through the side of said casing, a rotary disk seated on said bolt, means carried by said disk normally disengaged from but adapted to engage and reciprocate said bolt, a tumbler-fulcrum and a spring-tension pin mounted on said offset portion, a plurality of tumblers and tumbler-springs mounted on said pins respectively, a catch carried by said disk adapted to coöperate with said tumblers, and a socket-plate.

45 50 55 60

6. In a lock, the combination of a casing composed of superposed cylindrical portions of different diameters connected by an offset portion forming respectively a bolt and a tumbler-chamber, a bottom for said casing, a sliding bolt seated thereon and projecting through the side of said casing, a rotary disk seated on said bolt, means carried by said disk normally disengaged from but adapted to engage and reciprocate said bolt, a tumbler-fulcrum and a spring-tension pin mounted on said offset portion, a plurality of tumblers and tumbler-springs mounted on said pins respectively, a catch carried by said disk adapted to coöperate with said tumblers, a steadyng-piece carried by said disk, said pins, said catch and said steadyng-piece extending into en-

gagement with the closure of said lock, and a socket-plate.

7. In a lock, the combination of a casing, a plurality of oppositely-sliding bolts seated therein and projecting through the sides thereof, springs acting on said bolts respectively, said bolts being spaced apart and having ways on the upper face thereof, a rotary disk seated on said bolts, downwardly-projected rounded studs eccentrically disposed on said disk, means whereby said disk may be rotated and a socket-plate.

8. In a lock, the combination of a casing, a plurality of oppositely-sliding bolts seated therein and projected through the sides thereof, springs acting on said bolts respectively, said bolts being spaced apart and having ways in the upper face thereof, a rotary disk seated on said bolts, downwardly-projected rounded studs eccentrically disposed on said disk, shoulders on said bolts respectively adapted to engage said casing and an abutment in said casing, means whereby said disk may be rotated and a socket-plate.

9. In a lock, the combination of a casing, a key-stud carried thereby, spring-seats on opposite sides of said casing, a plurality of oppositely-sliding bolts seated in said casing between said stud and said spring-seats respectively and projected through said casing, springs acting on said bolts respectively, said bolts being spaced apart and each having ways on the upper and the lower faces thereof, a link pivotally mounted on said stud and engaging said lower ways, a rotary disk seated on said bolts, downwardly-projected rounded studs eccentrically disposed on said disk, means whereby said disk may be rotated and a socket-plate.

100 105

10. In a lock, the combination of a cylindrical casing, a sliding bolt seated therein and projecting through the side thereof, spring acting on said bolt, means whereby said bolt may be reciprocated, and a circular socket-plate, said bolt on its outer edge being curved to conform to the contour of said casing and said socket-plate.

11. In a lock, a casing composed of two superposed cylindrical portions connected by an offset portion, the lower of said cylindrical portions being smaller in diameter than the upper, a plurality of tumblers mounted in said upper cylindrical portion and a bolt-actuating mechanism mounted in said lower portion.

110 115

In witness whereof I have hereunto affixed my signature, this 27th day of August, 1903, in the presence of two witnesses.
